Gardner D. Pearson ATTORNEY.

UNITED STATES PATENT OFFICE.

HARRY METCALFE, OF SOMERSWORTH, NEW HAMPSHIRE.

PROCESS AND MACHINE FOR CONTINUOUS DYEING.

Application filed January 3, 1922. Serial No. 526,731.

To all whom it may concern:

Be it known that I, HARRY METCALFE, a citizen of the United States, residing at Somersworth, in the county of Strafford and State of New Hampshire, have invented certain new and useful Improvements in Processes and Machines for Continuous Dyeing, of which the following is a specification.

This invention relates to processes and machines for the continuous dyeing of cloth. It has special reference to dyeing of cotton cloth, but may be adapted for use with wool, silk, or other material.

In continuous machine dyeing of cloth, the dye is mixed in a vat and the cloth is run end for end through the vat under rollers therein, the excess of dye being squeezed out as the cloth advances. It may then be passed through a fixing vat of chrome or other similar material and be washed at the end or at other stages of the process.

On account of the fact that in order to obtain the desired shades, dyes of different colors must be mixed together and that such mixture is not strictly a chemical combination, it is found that the cloth has more affinity for one of the component colors than for another and for this reason has a tendency to take up more of that shade than the others.

The result of this is that the end of the cloth which first passes through the dye and other vats has a different shade from that which comes through at the end.

In the effort to obtain a strip of cloth of the same shade from one end to the other, the practice has been to add to the dye liquor enough of the color for which the cloth has the most affinity to even up the excess amount of that shade absorbed by the cloth, but it has been found impossible to so graduate the addition of such dye as to make the resulting color of cloth uniform throughout the strip.

The purpose of my invention is to provide a process and, preferably, a machine for carrying out the process, whereby the cloth, or at least one surface thereof, shall be of exactly a uniform shade from end to end. It is especially useful for relatively thick cloth.

I accomplish this purpose by using in connection with the usual dye box an independent tank or reservoir in which the same shade or color is mixed, but through which the cloth does not pass, and preferably I keep

the dye in this tank at all times well mixed and conduct it to a point just before the cloth enters the squeeze rolls, where this supplementary dye is sprayed or sprinkled on the surface of the goods.

As this supplementary dye is sprinkled on the cloth, instead of the cloth being passed through it, there is nothing to change the shade, and as it is sprinkled at least over one surface and, preferably, forced through the entire body of the cloth by the heavy squeeze rolls, it is apparent that when the cloth leaves the squeeze rolls it will continue to have a uniform color throughout, or at least on one surface.

The advantages of my process and machine are that a practically unlimited amount of cloth can be dyed exactly the same color, and there is a substantial saving in the amount of dye necessary.

My process and machine are particularly useful for dyeing cotton cloth or other textile material composed of vegetable fiber more or less similar to cotton. It may be used for wool, silk, or other animal fiber, but the process of dyeing such material is different as it has a different affinity for the dye and there is therefore not as much need for my process. In addition to securing a more uniform color, my process uses less dye. In the old system the cloth passes through the dye and absorbs part of the color. The rest of the dye in the tank is off shade and is therefore allowed to overflow and is thrown away as no use has been found for it, while in my process, by proper regulation there is little if any overflow as all the dye is taken up by the cloth.

With a suitable device and proper adjustment, the amount of dye delivered for the face color can be of such quantity that the amount squeezed out by the finishing rolls will exactly equal the amount of basic color taken up by the undyed cloth as it enters the dyeing apparatus, with the result that there is no overflow and no waste.

I can preferably also so adjust the delivery of the fixing color or chrome that there will be little, if any, drip from the squeeze rolls into the vat, and there will therefore be no overflow of chrome. It is therefore obvious that the dye and chrome are saved by my process.

In the present system of dyeing, the cloth

is fed in so that the back is in contact with the bottom dye vat rolls thereby bringing the face nearer the sediment, if any, at the bottom. I reverse this and carry the face of my cloth in contact with the rolls thus causing the back to be down at the bottom nearest whatever sediment there may be. The face is therefore protected and more free from specks and stains.

10 In the drawings, Fig. 1 is a diagrammatic side elevation of the preferred arrangement of my apparatus for carrying out my process in the most approved manner in the chrome dyeing of cotton cloth.

15 Fig. 2 is a diagrammatic plan view of the dye box or main dye tank and the fixing and washing tanks or vats.

20 Fig. 3 is a vertical section from the side of the squeeze rolls, showing their nip and the sprinkler.

25 Fig. 4 is a section from the front on the line 4—4 of Fig. 3.

30 Fig. 5 is a view of the sprinkler K from the other side of line 4—4 from that shown in Fig. 4.

35 Fig. 6 is a diagrammatic side elevation of a single dye box not associated with washing or fixing vats.

40 Fig. 7 is a sectional side elevation similar to Fig. 3 of a modification of my machine showing another way of carrying out my process.

45 Fig. 1 represents a floor and 2 represents the floor above of any suitable building, or 2 might indicate a raised platform.

50 On the floor 1, I show dye box A next to which are the two washing machines or water tanks B¹ and B², beyond which is the fixing vat C and beyond this the final washing machine or washing tank D. In each tank there is a series of bottom rollers 10 and top rollers 11 which may be idle or driven and of suitable length to permit the cloth, such as F, to pass under bottom rollers 10 and over top rollers 11.

55 The cloth F is shown as passing down under a friction bar 3, thence over a measuring roll 4, thence under another friction 5 and over friction bar 6. It passes thence under and over the rolls 10 and 11 in dye box A, and in the middle of its course preferably up over the large squeeze roll I, thence back again and finally from the top roll 9 back between the squeeze rolls H and G, thence up over an elevated series of rolls 15 which permit the air to reach it for oxidation.

60 The dye box A preferably has at the bottom a series of steam coils 118 and the overflow outlets 12, one arranged above the other so that the height of the dye in the box can be regulated by opening or closing the overflow outlets.

65 Preferably, the top and bottom squeeze rolls H and I are of cast iron and the middle roll G is rubber covered, and these rolls

are pressed together by their own weight or by pressure mechanism indicated as springs L. Located at a high point on the next floor or platform is the auxiliary dye tank X shown as containing a steam coil 73, by 70 which the dye is heated and agitated, and as having a delivery pipe 16 and control valve 74.

75 I preferably use two or more dye mixing tanks 70 and 70, each having outlet 72 with control valve 71 whereby the dye can be mixed in one while it is being delivered from the other into the tank X. By this arrangement the supply of dye can be kept continuously uniform in quantity and color.

80 Auxiliary dye delivery pipe 16 has a regulating valve 17 and connects with a sprinkler pipe K positioned over the cloth as it runs from the roll 9 to the nip of the rolls G and H and close up thereto. The delivery 85 holes 19 of sprinkler K are of such size and the delivery of the dye so regulated that it is spread out evenly on the cloth by the pressure rolls G and H and any excess runs down over the cloth and roll 9 into the dye 90 box A. The quantity can be so regulated, however, that there is very little, if any, to run out of the overflow outlets 12.

95 From the rolls 15, the cloth passes over an idle roll 20 under and over the rolls 10 and 11 in the first washing machine tank B¹, thence up over between squeeze rolls G and H down into the second washing machine tank B², thence being squeezed by other squeeze rolls H and G into the fixing tank C. 100

105 The fixing tank C is preferably provided with steam coil 48 and an outlet 49 which may be at a lower level than that of the washing machines, and the cloth passes under rolls 10 and over rolls 11, thence between squeeze rolls H and G into the final washing machine tank D under rolls 10 and over rolls 11, thence through squeeze rolls H and G up and over reels 100, 100, thence on to a delivery truck P.

110 Preferably, the water pipe Y is provided with branches 22, 32 and 52 which extend horizontally into tanks B¹, B² and D and has vertical connections 23, 33 and 53 with regulating valves 24, 34 and 54 for the lateral water sprinklers 26, 36 and 56 arranged directly in front of the nip of the respective squeeze rolls H and G. The cloth is thus washed just before it is squeezed in all of the washing machines. Tanks B¹, B² and D may be provided with overflow outlets 29, 39 and 59 at a suitable height.

115 Z represents an auxiliary fixing tank which may be kept continuously supplied by means of two or more mixing tanks 80, 80, each having a delivery spout 82 and shut-off valve 81. The fixing material such as chrome may be mixed in the tanks 80, 80 and continually delivered in uniform strength from tank Z through pipe 85, the supply being 120 125 130

regulated by valve 84. 88 is a fixing sprayer to which pipe 85 delivers, the supply being further regulated by valve 86. This spray is directed upon the cloth just before it reaches the nip of the squeeze rolls H and G.

The dye box A may be filled independently or, preferably, from auxiliary dye tank X and pipe 16 through the branch 7 controlled by valve 18, and in the same way the fixing tank C can be filled independently or from tank Z through pipe 85, the supply being controlled by valve 87.

All of the squeeze rolls H and G are substantially the same and the sprinklers 26, 36, 15 56, and 88 are substantially the same as dye sprinkler K.

Where cloth of different widths is being run through, the holes in each sprinkler may, as indicated at M in Fig. 5, be covered 20 up so that less dye, water or chrome will be wasted.

In Fig. 6, I show a dye box used alone without washing machines or fixing tanks, with only two squeeze rolls H and G, the 25 roll I being omitted and the cloth passing under and over rolls 10 and 11 and from the last roll 11 up between the squeeze rolls.

Such an arrangement can be used, although I prefer the one shown in Fig. 1.

30 It is obvious that my process might be used with various other machines and with various other arrangements of parts.

For instance, as shown in Fig. 7, instead of a sprinkler such as K for the dye, I might 35 pass the cloth F from the dye box over a roll 92, thence down under another roll 91 which almost fills a shallow dye tank 90 kept supplied with dye from another body of dye, such as a tank like X, whereby the cloth, after 40 being submerged in one body of dye to produce the base color, will then have its surface treated with dye from another body of dye to produce an uniform face color.

I prefer that at the nip of the squeeze rollers there should be enough basic and finishing dye to completely saturate the cloth, the dye being forced between the threads and perhaps into the fiber.

I may, however, instead of delivering so 50 much finishing dye as would be squeezed entirely through from the back to the front of the cloth, use a smaller quantity delivered or sprayed on the face 95 of the cloth, as indicated in Fig. 6, with the result that this 55 face is of uniform color even if the back is not.

It is obvious that in whichever manner the cloth is treated from one body of dye to produce a base color, the final color, either of 60 both faces or of one, is determined by the application of the color from another body of dye in the manner described. The dye from the second body may be delivered in a fine spray instead of sprinkled so that there 65 will be little if any forced through the cloth,

and the face of the cloth may therefore have a finishing color different from the basic color and the back.

My machine and process, however, are particularly useful for comparatively thick 70 or heavy cloth into which the color must be forced and which is made of material which has an affinity for some of the dye components more than for others.

I claim:

1. The process of uniformly dyeing a strip of cotton cloth which consists of passing it from one end continuously through one main body of dye, then sprinkling on the back thereof dye from another body of 80 dye, then squeezing the cloth so that the dye will be driven through the cloth uniformly, then treating it with fixing material and washing it.

2. The process of uniformly dyeing a strip of cotton cloth which consists of passing it from one end continuously through one body of dye, then sprinkling it with dye from another body of dye, then squeezing the cloth, then treating it with fixing material 90 and then washing it.

3. The process of uniformly dyeing cloth which consists of submerging it in one body of dye to produce a base color, and then 95 sprinkling the surface with dye from another body of dye to produce a uniform face color.

4. The process of uniformly dyeing cloth which consists of submerging it in one body of dye to produce a base color and then 100 applying to the cloth outside said body of dye dye from another body of dye to produce a uniform face color.

5. The combination in a machine for continuously dyeing a strip of cloth an uniform color, of a dye box having submerged rollers, squeeze rollers located over the tank in position where the excess of dye will drop therein; with an auxiliary dye tank and means for agitating the dye therein, 110 an outlet pipe therefrom, a sprinkler attached to said outlet pipe with its holes in position to sprinkle dye on the cloth after it has left the dye box just before it passes between the squeeze rolls; elevated rolls; a 115 washing tank having submerged rolls, squeeze rolls, and a sprinkler located adjacent said rolls; a fixing tank having submerged rolls, and squeeze rolls; and an independent source of fixing material and a 120 sprinkler adjacent the squeeze rolls connected therewith; together with a final washing tank having submerged rolls, squeeze rolls and a sprinkler.

6. The combination in a machine for continuously dyeing a strip of cloth an uniform color, of a dye box having submerged rollers, squeeze rollers located over the tank in position where the excess of dye will drop 125 therein; with an auxiliary dye tank and 130

means for agitating the dye therein, an outlet pipe therefrom, a sprinkler attached to said outlet pipe with its holes in position to sprinkle dye on the cloth after it has left the dye box just before it passes between the squeeze rollers; and means for regulating the flow of the dye through said sprinkler.

7. The combination in a machine for continuously dyeing a strip of cloth an uniform color; of a dye box containing one body of dye and means for submerging the cloth therein; with squeeze rollers located over the tank in position where the excess of dye will drop therein; an auxiliary dye tank containing another body of dye; an outlet pipe therefrom; and a sprinkler attached to said outlet pipe with its holes in position to sprinkle dye on the cloth after it has left the dye box just before it passes between the squeeze rollers.

8. The process of uniformly dyeing a strip of cotton cloth which consists of passing it

from one end continuously through one body of dye, then sprinkling it with dye from another body of dye, then immediately squeezing the cloth to so expel the excess of dye that it will merge with the dye from the first body, then treating it with fixing material, and then washing it.

9. The process of uniformly dyeing a strip of cloth which consists of passing it from one end continuously through one body of dye, then distributing outside said body of dye dye upon it from another body of dye, and then immediately squeezing the cloth to so expel the excess of dye that it will merge with the dye from the first body.

10. The process of uniformly dyeing cloth which consists of treating it with one body of dye to produce the base color, and then applying to the cloth outside said body of dye dye from another body of dye to produce a uniform face color.

HARRY METCALFE.
